FEEDING AND STACKING MACHINE

Louis L. Matthews, Westerly, R. I., assignor to
Maxson Automatic Machinery Company, West-
erly, R. I., a corporation of Rhode Island

Application May 17, 1947, Serial No. 748,813

7 Claims. (Cl. 271—88)

1

The present invention relates to feeding-and-stacking machines, and more particularly to machines for feeding and stacking sheet material, like paper.

A machine of the above-described character in common use comprises a plurality of tapes for feeding the sheets into a lay-boy, where they become stacked upon a main support. The main support is automatically lowered by degrees to maintain the top of the stack of sheets at substantially constant height, thereby permitting the feeding means to continue feeding the sheets into the lay-boy on top of the stack without hindrance from the sheets already there. When the main support becomes lowered to the floor, however, it becomes necessary to remove it, and to substitute therefor a new main support on which to stack further sheets. It is essential, at such times, either to shut down the machine, so as to prevent the feeding of further sheets into the lay-boy, or else, if it is desired not to interrupt the continuous feeding of the sheets, to provide an auxiliary support on which temporarily to stack the sheets during the removal of the completed stack on the main support and the substitution therefor of a new main support, after which the sheets temporarily stacked on the auxiliary support must be transferred to the substituted main support.

An object of the present invention is to provide a new and improved feeding-and-stacking machine adapted for the employment of a new and improved auxiliary support.

A further object is to provide new and improved means for supporting the auxiliary support at times when it is used for the stacking of sheets thereon and during the removal of the stack of sheets and the replacement therefor of a new main support.

Another object is to provide a new and improved machine of the above-described character especially adapted for the feeding and stacking of long sheets.

Other and further objects will be explained hereinafter and will be particularly pointed out in the appended claims.

The invention will now be more fully described in connection with the accompanying drawings, in which Figs. 1 and 1A together constitute a diagrammatic view in side elevation, with parts broken away, for clearness, of a paper-cutting-and-feeding machine embodying the present invention, an intermediate portion of the machine being omitted between the lines A—A, and the fingers constituting the auxiliary support being

2

shown retracted; Fig. 2 is a section taken upon the line 2—2 of Fig. 3, looking in the direction of the arrows; Fig. 3 is a plan of the left-hand portion of the machine shown in Figs. 1 and 1A, the auxiliary supporting fingers being shown extended, with a portion of a sheet resting thereon; Fig. 4 is an end elevation, looking from the left of Figs. 1, 1A, 2 and 3; Fig. 5 is a section taken upon the line 5—5 of Fig. 3, looking in the direction of the arrows; Fig. 6 is a section similar to Fig. 2, upon a larger scale, showing the auxiliary supporting fingers partly extended; Fig. 7 is a section, upon a still larger scale, taken upon the line 7—7 of Fig. 3, looking in the direction of the arrows; Fig. 8 is a section taken upon the line 8—8 of Fig. 7, looking downward in the direction of the arrows; Fig. 9 is an elevation looking from the left of Fig. 7; Fig. 10 is a section similar to Fig. 7, with the parts in relatively different positions; Fig. 11 is a section taken upon the line 11—11 of Fig. 7, looking in the direction of the arrows; Fig. 12 is an elevation of a detail showing the rear support for the supporting fingers, looking from the left, as viewed in Figs. 4 and 5, but upon a larger scale; Fig. 13 is a section taken upon the line 13—13 of Fig. 3, looking in the direction of the arrows, upon a larger scale; Fig. 14 is a view looking from above, in Fig. 12; Fig. 15 is an elevation, partly in longitudinal section, upon an enlarged scale, of one of the auxiliary supporting fingers; Fig. 16 is a fragmentary side elevation of a portion of the machine in a diagrammatic view of circuits for controlling the operation of extending and retracting the auxiliary supporting fingers, the supporting fingers being shown retracted; Fig. 17 is a view similar to Fig. 16, showing the supporting fingers extended; Fig. 18 is a diagrammatic view illustrating the feeding of sheets on to a main support in the lay-boy, the auxiliary supporting fingers being retracted; Fig. 19 is a similar view, showing the accumulation of the stack of sheets on the main support, at a later time; Fig. 20 is a similar view, showing the stack of sheets on the main support completed and the feeding of further sheets on the extended auxiliary fingers; pending the removal of the main support with the stack of sheets thereon; Fig. 21 is a view similar to Fig. 20, showing the main support with the stack of sheets thereon removed and a new main support substituted therefor; Fig. 22 is a view similar to Fig. 21, showing the substituted main support raised into position ready to receive the sheets temporarily accumulated on the supporting fingers upon the retraction of the

supporting fingers; and Fig. 23 is a fragmentary perspective, upon a larger scale.

The drawings illustrate a paper-sheet-cutting-and-feeding machine of well-known type, such as is commonly employed in paper mills, to cut webs from a roll or rolls into sheets, and feeding the sheets by means of more or less horizontal conveyor tapes, into a lay-boy.

A web 32 is led from a paper roll (not shown) of paper to feed rolls 10, by which the paper is advanced to a stationary bed-knife cutter 15. The term "web," "paper," "sheet" or its equivalent, will be employed herein to denote either a single layer or a plurality of superposed layers of the paper or other material. A rotary cutter 16 cooperates with the bed cutter 15 to cut the traveling web into sheets 56 of the desired length. The invention is equally applicable to machines for feeding previously cut sheets.

Owing to the feeding action of the rolls 10, aided by gravity, the sheets 56 travel, at a downward incline, toward a series of cooperating conveyor tapes or belts 2 and 6. The plurality of conveyor tapes or belts 2 and 6 and the rotary cutter 16 are actuated by any desired mechanism 11. The conveyor tapes or belts 6 are disposed approximately horizontal, at a level below the level at which the web 32 is fed between the rolls 10, but they may be inclined slightly upward, to slope toward the lay-boy 4. Together with the bed-knife cutter 15 and other parts of the machine, the tapes or belts 2 and 6 are mounted on a frame 26 to the rear of the lay-boy 4.

As shown clearly in Figs. 18 and 19, the tapes 2 and 6 feed the sheets 56 forward in order to deliver them singly into the lay-boy 4 upon a main skid support or platform 11, for stacking and piling. The tapes 2 and 6 are naturally above the level of the main support 11 in the lay-boy 4. Fig. 18 represents the condition shortly after the rotary cutter 16 and the tapes 2 and 6 have been started operating. The main skid support or platform 11 has been raised to its highest position and sheets 56 have begun to be stacked thereon. Fig. 19 represents a later stage, after a considerable number of sheets 56 have become stacked on the skid support or platform 11.

In the lay-boy 4, the sheets 56 engage front stops 25, Figs. 1 to 4 and 6, to limit their further forward movement. The sheets are jogged by side jogger blades 5, in the usual manner. The side jogger blades 5 and rear joggers 7, in combination with stationary fingers 8, assure that the sheets 56 shall be stacked or piled evenly. Constructions for effecting this result are described, for example, in Letters Patent 2,261,972, issued November 11, 1941, and 2,367,416, issued January 16, 1945, to Louis L. Matthews. The joggers and other parts are omitted from the diagrammatic Figs. 18 to 22, for clarity.

The length of the sheets that may be stacked or piled in the lay-boy is determined by the position of the front stops 25. The stops 25 should therefore be adjustable. They are shown carried upon brackets that are hooked over the vertical leg 13 of a transversely disposed L-shaped arm of a carriage in which is rotatably mounted a similarly transversely disposed shaft 14, the ends of which carry gears 17. Fig. 6 shows the shaft 14, upon a larger scale, resting on the horizontal leg 60 of this carriage. The gears 17 mesh with fixed longitudinally disposed racks 18. Rotation of the shaft 14, through the intermeshing arrangement of the gears 17 and the

racks 18, will result in adjustment of the carriage 13, 60 lengthwise of the machine, thus effecting corresponding adjustment of the stops 25.

The main skid support or platform 11 is initially raised to a level just below that of the delivery tapes 2 and 6, as shown in Fig. 18. As the sheets continue to be fed into the lay-boy 4, and become stacked or piled on the main support 11, the main support 11 becomes automatically lowered, by degrees, in order to maintain the level of the stack or pile of sheets 56 approximately uniform. This may be effected in any desired manner, as under the control of oscillatory hooked members 12, as described, for example, in Letters Patent 1,545,912 issued July 14, 1925, to Charles B. Maxson. In time, the support will become lowered, through the position illustrated in Fig. 19, to the floor, as shown in Fig. 20. One of two procedures becomes thereupon possible. Either the machine must be shut down, until the main support 11, with the stack or pile of sheets 56 thereon is removed, and a new main support 11 is substituted therefor, and raised into the position of Fig. 18, or else an auxiliary support for the oncoming sheets 56 must be provided, on which the sheets 56 may continue to be stacked or piled temporarily, for subsequent transfer to the substituted main support 11.

Auxiliary-support proposals have heretofore been made, among them the proposal that the auxiliary support be confined normally within the framework 26 below the tapes or belts 2 and 6, and to the right of the lay-boy 4, as viewed in Figs. 1 and 1A. Part of this framework is not shown, as it is contained between the lines A—A. The proposal has involved moving the auxiliary support out from within the confines of the framework 26, toward the left, as viewed in Figs. 1 and 1A, into the lay-boy 4, when it is desired to remove the main support 11 and to replace it with a new main support 11.

As will be understood from Fig. 20, however, there is not very much room between the top of the completed stack and the line of delivery of the sheets 56 into the lay-boy 4 into which to interpose such an auxiliary support. Fig. 20, indeed, has purposely been distorted, for purposes of clarity, to show relatively much more room than actually obtains, in practice. The stacks may be three to six feet high. This proposal, therefore, would either involve redesigning the machine, to provide more vertical space in which to position a more sturdy auxiliary support, or else it would be necessary to employ an auxiliary support of so weak a nature that it would not be able to support very many temporarily stacked or piled sheets, particularly if the sheets are rather long.

Neither of these expedients is satisfactory. The former has involved increasing the size of the machine to accommodate a heavy I-beam auxiliary support; or, at least, an auxiliary support that is of quite thick dimension at the place where it is held to the machine. As for the latter proposal, many a temporary stack or pile of sheets, particularly long sheets, or even short sheets if sufficiently heavy, has slipped off the auxiliary support and on to the floor, due to its flexing or sagging under the weight of the sheets by the time that the main support 11 and the stack or pile of sheets thereon has been removed and a new main support 11 has been substituted therefor.

According to the present invention, the auxil-

iary support for temporarily receiving the sheets 56 during the removal of the completed stack and the replacement of a new main support 11 is constituted of a plurality of horizontally disposed supporting fingers 28 arranged in the form of a grid disposed normally just below the tapes 2 and 6 from side to side of the machine. The fingers 28 are of relatively small cross-dimension vertically. A very satisfactory form that the fingers may assume is $\frac{3}{4}$ inch-diameter tubing. A space of $\frac{3}{4}$ inch is available above the top of the completed stack shown in Fig. 20 and below the level of the path of feed of the sheets 56 at the time that the sheets 56 are delivered by the tapes 2 and 6 thereabove into the lay-boy 4. The fingers may be about $2\frac{1}{2}$ inches apart. The forward free ends of the tubing fingers 28 are plugged, as shown more particularly at 30, in Fig. 15. The rear ends of the tubing fingers 28 are secured to the transversely disposed bar of a carriage 3, Figs. 1A to 5 and 12 to 17.

The transversely disposed bar of this carriage 3 is provided at its ends with guide plates 34 each having a pair of upper and a pair of lower guide rollers 36. The guide plates 34 are mounted to slide along longitudinally disposed tracks 38, one at each side of the machine, the upper and lower pairs of rollers 36 respectively engaging the upper and lower surfaces of the tracks 38 for anti-friction purposes. The carriage 3 is thus slideable back and forth longitudinally of the machine.

The fingers 28 are normally retracted, within the confines of the frame 26, as shown in Figs. 1, 1A and 16. At the completion of a stack, however, the carriage 3 to which these rear ends are secured is actuated horizontally forward along the tracks 38 toward the lay-boy 4, in order to carry the fingers 28 beyond the stationary fingers 8 and the rear joggers 7, into the lay-boy 4, so as to dispose them just above the top sheet of the completed stack, and below the tapes 2 and 6, as illustrated in Figs. 2, 3 and 17. The fingers 28 are shown occupying an intermediately disposed position in Fig. 6.

The position of the supporting fingers 28 corresponding to that of Figs. 1, 1A and 16 is diagrammatically illustrated in Figs. 18 and 19. Upon the completion of the stack shown in Fig. 20, and just prior to the main support or platform 11 reaching the floor, the supporting fingers 28 are extended forward into the lay-boy 4 to the position of Figs. 2, 3 and 17. The support 11 is lowered the remaining short distance to the floor later, electrically or manually. The fingers 28 are extended forward very rapidly, so that the next following sheets 56 fed from between the tapes 2 and 6 will be received temporarily on these extending fingers 28, instead of on the stack below, and without shutting down the equipment. The tapes 2 and 6 continue to feed the sheets 56 on to the extending fingers 28, as is also illustrated in Fig. 20, during the removal of the main support 11, with the stack thereon, and the substitution therefor of a new main skid support 11, as shown in Fig. 21. The new main skid support 11 is thereupon raised, by means of a well-known lay-boy elevating table, not shown, to its uppermost position, just below and in contact with the extending fingers 28, as shown in Fig. 22. The extending fingers 28 are thereupon retracted, from the position diagrammatically shown in Fig. 22, to their original position, diagrammatically shown in Fig. 18. The sheets thus temporarily stacked on the extended fingers 28 become thereupon automatically lowered on to

10 15 20

the new main support 11, through the small vertical space corresponding to the thickness of the fingers 28.

Fingers 28 of so small-diameter tubing, being naturally very flexible, would be unable to carry the load of the sheets 56 temporarily stacked thereon, were it not for the support that they are accorded by the present invention, as will now be explained.

As illustrated upon a larger scale in Fig. 7, a two-armed pivoted member, of right-angular cross-section, extending from side to side of the machine, is normally so disposed that its angle is normally oriented toward on-coming fingers 28, with its upper or more or less upright arm 40 at the level of the horizontally disposed fingers 28, and tilting toward the right, as viewed in Fig. 1, toward the fingers 28. As the free plugged ends 30 of the fingers enter this angle, therefore, toward the limit of their forward movement into the lay-boy 4, they engage this upper arm 40 in order to effect pivotal movement of the angle member, tilting it backward, from the position of Fig. 7 into the position of Fig. 10. The other or more or less horizontally disposed arm 42, which normally inclines somewhat downward, is thus caused to pivot upward, thus to effect engagement of the undersides of the forward free ends 30 of the fingers 28, as shown in Fig. 10, thus turning them up and providing a support for the forward ends of the fingers. The pivotal movement of the angle-iron 40, 42 is limited by forward and rear stops 44 and 46.

This pivotal movement of the angle iron 40, 42 will take place irrespective of the point at which, within limits, the forward ends 30 of the fingers 28 engage the arm 40. In Fig. 7, the free ends 30 of several of the fingers 28 as shown out of horizontal alignment, as might occur if they should sag or vibrate during their advance into the lay-boy. They will all, however, become aligned horizontally, as shown in Fig. 10, by the arm 42 that supports them during the before-described temporary stacking of sheets 56 on the fingers 28.

The pivoting of the angle member 40, 42, may be effected in any desired way, as by means of pivot pins 50 projecting from plates 52 provided with angular grooves 54 in which the ends of the angle iron are fitted, as will be understood more particularly from Figs. 3, 7, 8 and 10.

The pivot pins 50 extend into pivot openings 48 disposed at the lower ends of the supporting arms 58. For purposes of assembly, each pivot opening is provided half in a block 58 and the mating half in a block 62 bolted to the supporting arm 58.

As the auxiliary support constituted of the supporting fingers 28 is thus supported at two points, spaced a considerable distance apart, by the carriage 3 and the angle iron 40, 42, there is no possibility for any sagging or flexing of the fingers 28, and they may therefore carry a considerable load. Though the angle iron 40, 42, moreover, normally occupies the position illustrated in Fig. 7, in which it is ineffective to support the front free ends 30 of the supporting fingers 28, it is the fingers 28 themselves, when they reach their forward limit of movement, that render the angle iron effective, by tilting it automatically into the position shown in Fig. 10.

It has been stated above that the machine may be adjusted to the handling of different-length sheets by adjusting the position of the stops 25.

It is necessary, of course, to adjust the position of the angle iron 40, 42 to correspond. All that is necessary, to this end, is to mount the angle iron 40, 42 upon the same carriage upon which is mounted the transversely disposed L-shaped arm 13, 60 that carries the front stops 25. The plates 52 for supporting the ends of the angle iron 40, 42 are therefore disposed at the lower ends of the arms 53, shown adjustably bolted to the ends of the supporting arm 13. When the operator adjusts the machine so as to set the front stops 25 for the particular-size sheets 56 fed and stacked in the machine, therefore, he at the same time automatically adjusts properly the position of the angle iron 40, 42 also. The vertical position of the angle iron 40, 42 may also be adjusted by bolting the supporting arm 58 at different vertical positions to the transversely disposed supporting arm 13, 60, as by means of the bolt-and-slot connections shown in Figs. 7, 9 and 10.

The same front stops 25 and the same side joggers 5 and rear joggers 7, therefore, that operate normally to even up the stack as the sheets 56 are fed on to the main skid support 11, therefore, operate also to even up the sheets 56 while they are being temporarily stacked in the auxiliary support constituted of the extending fingers 28. When the supporting fingers 28 are retracted, therefore, they will comb out from under the sheets 56 temporarily stacked thereon, and will travel back through the stationary fingers 8 and the rear joggers 7. The temporarily stacked sheets 56 will therefore become deposited on the substituted skid support 11 in an even uniform pile.

The rear joggers 7, the stationary fingers 8 and the hooked members 12 are disposed in the spaces between adjacently disposed fingers 28. The level of the fingers 28 is just above the bottoms of the stops 25, in order that the same stops 25 may serve during the stacking of both the main and the temporary stacks or piles of sheets 56. The main support 11, when first introduced into the lay-boy, is raised into contact with the bottoms of the stops 25. The retracted temporary pile, therefore, drops only a very small distance on to the new main support 11 when the fingers 28 are retracted.

The carriage 3 to which the rear ends of the extending supporting fingers 28 are secured is actuated back and forth, to move the extending fingers 28 into and out of the lay-boy 4, by means of two sprocket chains 64 the ends of which are secured to the opposite ends of the respective guide plates 34. The sprocket chains 64 each passes over sprocket wheels 66 and 68 and a sprocket-chain tightener 70. The sprocket wheels 66 are mounted at the opposite ends of a transversely disposed shaft 72 and the sprocket wheels 68 at the opposite ends of a similarly disposed shaft 74. The shaft 74 is driven from a motor 76 through connections 78 and a sprocket wheel 80 mounted upon the shaft 74. The supporting fingers 28 may therefore be actuated into and out of the layboy 4 merely by reversing the operation of the motor 76.

Assuming that the fingers 28 occupy the retracted position diagrammatically shown in Fig. 16, and that a stack has been completed on the main skid support 11, a switch 82 may be manipulated from the "in" position of Fig. 16 to the "out" position, as shown in Fig. 17. This sets the motor 76 into operation in one direction, in order to actuate the fingers 28 into the lay-boy 4, as

diagrammatically shown in Fig. 17, to a position just above the top of the stack supported by the main support 11, as illustrated in Fig. 20. The fingers 28 become thus positioned in the path of the feed of the sheets 56, in replacement for the top of the just-completed stack. The feeding of the sheets 56 may therefore continue, without interruption, the fingers 28, as before explained, constituting an auxiliary support for the sheets 56. A new stack of sheets, but much smaller than the regular stack before described, become thus temporarily deposited on this auxiliary support.

Upon the forward ends 30 of the fingers 28 tilting the angle iron 40, 42, from the position of Fig. 7 into the position of Fig. 10, a lever 84 will be actuated, in response to this tilting movement of the angle iron 40, 42, from the position of Fig. 16 into that of Fig. 17, thus causing the position of a front limit switch 86 to open the circuit for the motor 76 and deenergize a solenoid 88 for actuating a brake 90 that is normally released when the motor 76 is in operation, thus to stop the motor 76 short. This will overcome any tendency for the extending fingers 28 to over-travel. The front limit switch 86 thus determines the position of the fingers 28 above the main skid support 11 with the sheets stacked thereon, though the brake 90 aids in this determination. The front limit switch 86 and the lever 84, of course, are adjustable as a unit with the angle iron 40, 42, and the front stops 25, being mounted on the arm 58.

When, after a new skid support 11 has been placed in position, as illustrated in Fig. 22, it is desired to retract the fingers 28, so as to deposit the sheets 56 temporarily stacked thereon on to the new skid support 11, the switch 82 will be actuated from the "out" position, as shown in Fig. 17, to the "in" position, illustrated in Fig. 16. The motor 76 is thereupon actuated in the reverse direction.

As the free ends 30 of the fingers 28 become thus withdrawn from the angle iron 40, 42, they cannot help but re-tip the angle iron 40, 42, into the normal position, illustrated in Fig. 7. This is because of the weight that the free ends 30 of the fingers 28 impose on the arms 42 of the angle iron. This return tilting movement of the angle iron causes the lever 84 to return the limit switch 86, from the position illustrated in Fig. 17, to the original position illustrated in Fig. 16.

When the carriage 3 supporting the rear ends of the fingers 28 reaches its original position, an arm 92 projecting rearwardly thereof engages a rear limit switch 94 to open the circuit of the motor 76.

The angle iron 40, 42, serves a further function as a safety device to prevent injury to the operator or other person who may happen to be in the vicinity of the machine during the forward movement of the supporting fingers 28 into the lay-boy 4. These fingers 28 enter the lay-boy 4 at considerable speed. In the absence of the angle iron 40, 42, therefore, and if the brake 90 should happen not to operate perfectly, they may travel out forward beyond the front stops 25, to strike the head of a person who may happen to be standing in front of the lay-boy 4. The angle-iron 40, 42, insures that no such injury shall take place.

The present invention is adapted for the feeding and stacking of sheets of any practical length, of any weight stock. It may be employed, for

example, to feed and stack sheets 80 inches long and $\frac{3}{2}$ of an inch thick.

A description of many portions of the machine an understanding of which is not essential to an understanding of the present invention has purposely been omitted and many parts of the machine have purposely not been illustrated in order not to detract attention from the features of essential novelty. Fuller explanations of such portions of the machine will be found in the Letters Patent above referred to. It will be understood that the features of novelty may be embodied in other machines and in machines of other types and that modifications may be made by persons skilled in the art without departing from the spirit and scope of the invention as defined in the appended claims.

What is claimed is:

1. A sheet-feeding-and-stacking machine having, in combination, a main support for a stack of sheets, means for feeding sheets forward to the main support for stacking thereon, a carriage, an auxiliary support the rear end of which is mounted on the carriage, means for actuating the carriage to dispose the auxiliary support above the main support in the path of feed of the sheets in order that the feeding means may feed the sheets to the auxiliary support for stacking on the auxiliary support, normally ineffective means for supporting the forward end of the auxiliary support when the auxiliary support is disposed above the main support, and means controlled by the auxiliary support when disposed above the main support for rendering the supporting means effective.

2. A sheet-feeding-and-stacking machine having, in combination, a frame, a lay-boy in which a main support may be disposed, a plurality of tapes mounted on the frame above and to the rear of the lay-boy for feeding sheets forward into the lay-boy for stacking therein on the main support, a carriage, a plurality of fingers constituting an auxiliary support and the rear ends of which are mounted on the carriage so that the fingers are normally disposed under the tapes, means for actuating the carriage forward into the lay-boy to dispose the fingers above the main support below the tapes in order that the tapes may feed the sheets to the fingers for stacking on the fingers, normally ineffective means for supporting the forward ends of the fingers when the fingers are disposed above the main support, and means controlled by the fingers when disposed above the main support for rendering the supporting means effective.

3. A sheet-feeding-and-stacking machine having, in combination, a frame, a lay-boy in which a main support may be disposed, a plurality of tapes mounted on the frame above and to the rear of the lay-boy for feeding sheets forward into the lay-boy and stacking them therein on the main support, a stop for engaging the forward ends of the sheets in the lay-boy, a carriage, a plurality of fingers constituting an auxiliary support and the rear ends of which are mounted on the carriage so that the fingers are normally disposed under the tapes, means for actuating the carriage forward into the lay-boy to dispose the fingers above the main support below the tapes in order that the tapes may feed the sheets to the fingers for stacking on the fingers, normally ineffective means for supporting the forward ends of the fingers when the fingers are disposed above the main support, and means controlled by the fingers when disposed

above the main support for rendering the supporting means effective, and a common support for the stop and the normally ineffective supporting means, the common support being adjustable to adjust the machine for the feeding and stacking of different-length sheets.

4. A sheet-feeding-and-stacking machine having, in combination, a main support for a stack of sheets, means for feeding sheets forward to the main support for stacking thereon, a carriage, an auxiliary support the rear end of which is mounted on the carriage, means for actuating the carriage to dispose the auxiliary support above the main support in the path of feed of the sheets in order that the feeding means may feed the sheets to the auxiliary support for stacking on the auxiliary support, and a two-arm pivoted angle member disposed with its angle oriented toward the auxiliary support and with one of its arms in the path of forward movement of the auxiliary support, the auxiliary support entering the angle of the angle member at the limit of its forward movement and engaging the said arm in order to effect pivotal movement of the angle member and thereby to effect engagement of the auxiliary support by the other arm to provide a support by the said other arm for the forward end of the auxiliary support.
5. A sheet-feeding-and-stacking machine having, in combination, a frame, a lay-boy in which a main support may be disposed, a plurality of tapes mounted on the frame above and to the rear of the lay-boy for feeding sheets forward into the lay-boy and stacking them therein on the main support, a carriage, a plurality of horizontal disposed fingers constituting an auxiliary support and the rear ends of which are mounted on the carriage so that the fingers are normally disposed under the tapes, means for actuating the carriage horizontally forward into the lay-boy to dispose the fingers above the main support below the tapes in order that the tapes may feed the sheets to the fingers for stacking on the fingers, and a two-armed pivoted angle member disposed with its angle oriented toward the fingers and with one of its arms at the level of the fingers, the fingers entering the angle of the angle member at the limit of their forward movement and engaging the said arm in order to effect pivotal movement of the angle member and thereby to effect engagement of the fingers by the other arm to provide a support by the said other arm for the forward ends of the fingers.
6. A sheet-feeding-and-stacking machine having, in combination, a main support for a stack of sheets, means for feeding sheets along a predetermined path over the main support for stacking thereon, an auxiliary support for a stack of sheets, means for actuating the auxiliary support to a position above the main support in the path of feed of the sheets in order that the feeding means may feed the sheets to the auxiliary support for stacking on the auxiliary support, and a two-armed pivoted angle member disposed with its angle oriented toward the auxiliary support and with one of its arms in the path of forward movement of the auxiliary support in order that the forward end of the auxiliary support may be caused first to enter the angle of the angle member at the limit of the forward movement of the auxiliary support and then to engage the said arm in order to effect pivotal movement of the angle member and thereby to effect engagement of the

11

said forward end of the auxiliary support by the other arm to provide a support by the said other arm for the said forward end of the auxiliary support.

7. A sheet-feeding-and-stacking machine having, in combination, a frame; a lay-boy in which may be disposed a main support for a stack of sheets, a plurality of conveyor tapes mounted on the frame above and to the rear of the lay-boy for feeding sheets forward along a predetermined path into the lay-boy over the main support for stacking thereon, means for gradually lowering the support to maintain the top of the stack at substantially uniform height, a carriage, a plurality of horizontally disposed fingers constituting an auxiliary support for a stack of sheets, the rear ends of which are mounted upon the carriage in substantially a horizontal plane just below the conveyor tapes so that the fingers are normally disposed in substantially a horizontal plane just below the conveyor tapes, the fingers being of vertical cross-dimension small enough to permit of their interposition just above the top of the stack of sheets upon the main support but just below the path of travel of the sheets over the main support, means for actuating the carriage horizontally forward toward the lay-boy to interpose the fingers in the lay-boy in the said substantially horizontal plane at a position just above the top of the stack of sheets upon the main

5 support and just below the path of travel of the sheets over the main support in order that the conveyor tapes may feed the sheets to the auxiliary support for stacking on the auxiliary support; and a two-armed pivoted angle member disposed with its angle oriented toward the fingers and with one of its arms at the level of the fingers in the path of forward movement of the fingers in order that the forward ends of the fingers may be caused first to enter the angle of the angle member at the limit of the forward movement of the auxiliary support and then to engage the said arm in order to effect pivotal movement of the angle member and thereby to effect engagement of the forward ends of the fingers by the other arm to provide a support by the said other arm for the forward ends of the fingers.

LOUIS L. MATTHEWS.
